(57) **CLAIM**

The ornamental design for an ultrasonic catheter assembly, as shown and described.

DESCRIPTION

This application is related to U.S. patent application Ser. Nos. 29/736,680, and 29/736,695, each filed on Jun. 2, 2020. FIG. 1 is a top view of an ultrasonic catheter assembly showing our new design; FIG. 2 is a bottom view of the ultrasonic catheter assembly of FIG. 1; FIG. 3 is a right side view of the ultrasonic catheter assembly of FIG. 1; FIG. 4 is a left side view of the ultrasonic catheter assembly of FIG. 1; FIG. 5 is a first end view of the ultrasonic catheter assembly of FIG. 1 as viewed from the distal end toward the proximal end of the ultrasonic catheter assembly; and, FIG. 6 is a second end view of the ultrasonic catheter assembly of FIG. 1 as viewed from the proximal end toward the distal end of the ultrasonic catheter assembly. In the drawings, the broken lines are for the purpose of illustrating environment only and form no part of the claimed design. The broken lines in the drawings illustrate an ultrasonic catheter assembly and form no part of the claimed design.
